ADJUSTABLE COUPLING SYSTEM

Leslie F. Curtis, Great Neck, N. Y., assignor to
Hazeltine Corporation, a corporation of Delaware

Application December 31, 1942, Serial No. 470,773

10 Claims. (Cl. 173—44)

The present invention relates to adjustable coupling systems and, particularly, to such systems of the type which are adapted to adjust the magnitude and polarity of coupling between at least two inductors.

Two inductors which are inductively coupled are said to have "mutual" inductance. Where the inductors are aperiodic or nonfrequency-selective, the voltage induced in one usually has a phase angle of approximately 90 degrees with respect to the current in the other. It is frequently desirable in such aperiodic inductive-coupling systems that the voltage induced in one inductor shall be in the same or opposite phase with the current in the other inductor and that this phase relationship shall not appreciably change with adjustment of the amount of coupling between the inductors over a predetermined range. Additionally, in certain applications it is desirable that the induced voltage shall be proportional to the square of the operating frequency. Where the induced voltage is in the same or opposite phase with the applied current as previously described, the inductive-coupling system may be said to have no reactive component of coupling but only a resistive component of coupling. That is, the system operates as though the coupling were effected by the use of a resistor. It is desirable that this resistance coupling of the system shall be controllable in magnitude without the use of any sliding contacts or flexible connections and it is frequently quite desirable that it shall be controllable from an effective positive resistance through zero to an effective negative resistance.

It is an object of the present invention, therefore, to provide a new and improved adjustable coupling system of the type described which possesses one or more of the desirable features hereinbefore specified.

It is a further object of the invention to provide a new and improved adjustable coupling system adapted continuously to adjust the magnitude, between positive and negative limits, of a resistive component of coupling between two inductors.

It is an additional object of the invention to provide an improved adjustable coupling system which is aperiodic or nonselective over a wide range of operating frequencies and which provides mainly resistive coupling between inductors of magnitude proportional to the square of the operating frequency.

It is a further object of the invention to provide an improved adjustable coupling system for continuously adjusting the magnitude and polarity 55

of resistive coupling between two inductors while avoiding the use of any sliding contacts or flexible connections.

In accordance with the invention, an adjustable coupling system adapted to operate over a given frequency range comprises a first and a second inductor, and a movable conductive nonmagnetic inductive-coupling means having a value of resistance greater than its value of reactance over the operating frequency range and being aperiodic and so disposed with reference to the inductors that in a given position in its path of motion it is substantially uncoupled with at least one of the inductors and in another position in its path of motion it is substantially coupled with both of the inductors, whereby the coupling means provides primarily resistance coupling between the inductors. The second inductor is so wound and disposed in the magnetic field of the first inductor that it has a predetermined minimum coupling with the first inductor for at least one position of the inductive-coupling means. The coupling system also includes means for moving the coupling means over at least a portion of its path of motion to adjust the value of the resistance coupling between the inductors.

In a particular form of the invention, the first inductor has two spaced portions connected to have opposing fields and the second inductor is positioned between these portions. The movable inductive-coupling means preferably has a ratio of resistance to reactance of the order of ten and preferably comprises a coupling cylinder wherein the desired high ratio of resistance to reactance is effected by a relatively thin cylinder wall.

For a better understanding of the present invention, together with other and further objects thereof, reference is had to the following description taken in connection with the accompanying drawing, and its scope will be pointed out in the appended claims.

Referring now to the drawing, Fig. 1 represents a cross-sectional view of an adjustable coupling system embodying the present invention; Fig. 2 illustrates a fragmentary portion of the Fig. 1 arrangement and shows the disposition and electrical connections of the inductors thereof; Fig. 3 is a graph representing the magnitude and polarity of coupling effected within the range of adjustment of the Fig. 1 coupling system; Fig. 4 represents a simplified equivalent circuit diagram of the Fig. 1 coupling system and is used as an aid in explaining the operation of the invention; Fig. 5 is a circuit diagram, partly schematic, of a complete electrical indicating system which embodies

the adjustable coupling system of the present invention; Fig. 6 illustrates a modified form of coupling cylinder suitable for use in the coupling system of the invention; Fig. 7 represents a modified form of the invention; and Fig. 8 is a graph representing the magnitude and polarity of resistance coupling effected by the Fig. 7 modification.

Referring now more particularly to Fig. 1 of the drawing, there is represented a complete adjustable coupling system embodying the present invention in a preferred form. The system includes a first inductor 10 having two spaced windings or portions 10_a and 10_b which are wound in suitable grooves 11 and 12, respectively, provided on the periphery of a cylindrical member or form 13 of insulating material. The coupling system also includes a second inductor 14 which is wound in an intermediate groove 15 of the member 13 and hence is coaxial with the first inductor 10 and centrally positioned between the portions 10_a and 10_b thereof. There is also provided in the coupling system an axially movable conductive nonmagnetic inductive-coupling means having a value of resistance much greater than its value of reactance over an operating frequency range and being aperiodic and so disposed with reference to the inductors 10 and 14 that in a given position in its range of motion it is substantially uncoupled with at least one of the inductors and in another position in its range of motion it is substantially coupled with both of the inductors, whereby the coupling means provides primarily resistance coupling between the inductors. This inductive-coupling means, which preferably has a ratio of resistance to reactance of the order of ten, comprises a coupling cylinder 16 of conductive material and the desired high ratio of its resistance to its reactance is effected by constructing it in the form of a relatively thin cylinder, the ratio of the cylinder wall thickness to cylinder external diameter being not substantially greater than one-seventh. The coupling cylinder 16 may be formed of any conductive nonmagnetic material, but the thickness of its cylinder wall should vary inversely with the specific conductivity of the material. Thus, if the coupling cylinder 16 is formed of brass, its wall may be relatively thick compared to that of a coupling cylinder formed of copper or aluminum.

The adjustable coupling system also includes means for moving the coupling means or cylinder 16 at least over a portion of its range of motion to adjust the value of the resistance coupling between the inductors. This means comprises a screw-threaded member 17 which is threaded through a flange 18, the latter having on its inner face a groove 19 in which the insulating member 13 is secured at one end. The flange 18 is provided with apertures 20 through which machine screws or the like may be inserted to secure the coupling system to a panel or other support. The member 17 is provided with a reduced end portion 21 which is slidably supported by a bearing member 22 secured within the other end of the insulating member 13. A cylinder 23 of insulating material is secured to the reduced portion 21 of the screw-threaded member 17 and carries the coupling cylinder 16. A manual adjusting knob 24 is secured to the screw-threaded member 17 for rotating the latter to move the coupling cylinder 16 with respect to the inductors 10 and 14.

The two portions 10_a and 10_b of the inductor 10 are connected and excited to have opposing magnetic fields. One manner in which this may be done is seen by reference to Fig. 2 which illus-

trates a fragmentary view of the Fig. 1 arrangement, corresponding elements in Figs. 1 and 2 being designated by similar reference numerals. The inductor portions 10_a and 10_b are wound in the same direction on the insulation member 13. One end terminal of the portion 10_a is connected to the corresponding end terminal of the portion 10_b and the other terminals of these portions are designated in Fig. 2 as *a* and *b*, respectively, and constitute the terminals of the inductor 10. Magnetic fields thus produced by the inductor portions 10_a and 10_b have opposing relation. The inductor portions 10_a and 10_b preferably have the same number of turns, whereby the position of zero magnetic field intensity occurs midway between them. The second inductor 14, in the position shown, is midway between the inductor portions 10_a and 10_b and hence is so disposed in the magnetic field of the first inductor 10 that the second inductor 14 is substantially uncoupled with the first inductor.

Considering now the operation of the adjustable coupling system, assume that the inductor 10 is excited by an alternating current. The opposed electromagnetic fields produced by the inductor portions 10_a and 10_b induce corresponding but opposite currents in the coupling cylinder 16, these currents at any given instant flowing around the periphery of the cylinder but in opposite directions. Assume further that the coupling cylinder 16 is positioned equidistant from the inductor portions 10_a and 10_b and that the magnetic fields produced by the latter are equal, as would occur if the inductor portions 10_a and 10_b had equal numbers of turns. The currents induced by these fields in the coupling cylinder 16 are then equal and the resultant fields which they produce are likewise equal but opposing and consequently are ineffective to induce any voltage in the centrally positioned inductor 14. It will be observed that inductor 14 is so wound and disposed in the magnetic field of inductor 10 that it has a predetermined minimum coupling with the inductor 14 for at least one position of the coupling means 16. In this embodiment, the minimum coupling is substantially zero when coupling means 16 is in a central position within inductor 14.

Assume now that the knob 24 is rotated to move the coupling cylinder 16 axially to a position where it is closer to the inductor portion 10_a than to the inductor portion 10_b. The coupling cylinder 16 is now more closely coupled to the inductor portion 10_a and the magnetic field produced by current flowing through the latter induces a current in the coupling cylinder 16 which is larger than that induced by the field of the inductor portion 10_b. The fields produced by these unequal induced currents are correspondingly unequal and the cylinder 16 now produces a resultant field which is effective to induce an alternating potential in the inductor 14. Due to the high ratio of resistance to inductive reactance of the coupling cylinder 16, the currents induced in the latter are in phase with the corresponding currents of the inductor portions 10_a and 10_b and the potential induced in the inductor 14 is therefore approximately in phase with the largest induced current in coupling cylinder 16. Under the conditions assumed, the induced potential in inductor 14 is approximately in phase with the current in the inductor portion 10_a. This potential has a magnitude which increases as the coupling cylinder 16 is moved more closely to the inductor portion 10_a. If now the coupling

cylinder 16 is moved to a position where it is more closely coupled to the inductor portion 10b than to the inductor portion 10a, the current induced in the coupling cylinder by the inductor portion 10b is larger than that induced by the inductor portion 10a, and the resultant electromagnetic field induces a voltage in the inductor 14 which, under the conditions last assumed, is approximately in phase with the current flowing in the inductor portion 10b. As before, the magnitude of this induced voltage varies with the closeness of spacing of the coupling cylinder 16 to the inductor portion 10b. That is, the coupling cylinder 16 effects a coupling between the inductor 14 and one of the inductor portions 10a, 10b.

The manner in which the magnitude and phase of the voltage induced in the inductor 14 by current flowing in the inductor 10, and thus the coupling between inductors 10 and 14, varies with movement of the coupling cylinder 16 is represented by the graph of Fig. 3. It will be seen from this figure that the induced voltage and coupling are zero when the coupling cylinder is centered with relation to the inductors 10 and 14 and that it has a given phase and a magnitude which increases with movement of the coupling cylinder in either direction from center. From this it will be seen that the adjustable coupling system of the invention is effective to provide primarily resistance coupling between the inductors 10 and 14 and that this resistance coupling may be either positive or negative; that is, it is equivalent to coupling produced by a resistor selectively having either a positive resistance or effectively a negative resistance.

It may be stated at this point that the magnitude of the voltage induced in the inductor 14 varies not only with the relative position of the coupling cylinder 16, as previously described, but varies also with the frequency of the current flowing in the inductor 10. Specifically, the induced voltage varies as the square of the operating frequency. This will be more readily apparent from the following mathematical analysis of the operation of the coupling system which considers the coupling cylinder 16 as equivalent to a small inductor and a large resistor serially connected in a closed circuit. Referring to Fig. 4, which represents a simplified equivalent circuit diagram of the coupling system of the present invention, the inductor L_{10} represents the inductor 10 which comprises the inductor portions L_{10a} and L_{10b} , the inductor L_{14} represents the inductor 14, and the inductor L_{16} and resistor R_{16} represent an inductor and resistor equivalent to the corresponding constants of coupling cylinder 16. The resultant mutual inductance between the inductor 10 and the coupling cylinder 16 is indicated in Fig. 4 as M_{10-16} . The mutual inductance between the cylinder 16 and the inductor 14 is represented in Fig. 4 as M_{16-14} . It will be understood that no mutual inductance exists between inductors 10 and 14.

It can be shown that the voltage induced in the coupling cylinder 16 by current flowing in the inductor 10 has the following value:

$$E_{16} = j\omega I_0 M_{10-16} \quad (1)$$

where

I_0 =the current flowing in the inductor 10,

$\omega=2\pi f$,

f =the frequency of the current I_0 ,

$j=\sqrt{-1}$

The resultant current which flows in the coupling

cylinder 16 due to this induced voltage is determined by the relation:

$$I_{16} = \frac{j\omega I_0 M_{10-16}}{R_{16} + j\omega L_{16}} \quad (2)$$

The voltage induced in the inductor 14 by the resultant current flowing in the coupling cylinder 16 is determined by the relation:

$$E_{14} = \frac{-I_0 \omega^2 M_{10-16} M_{16-14}}{R_{16} + j\omega L_{16}} \quad (3)$$

Now since:

$$M_{10-16} = k_{10-16} \sqrt{L_{10} L_{16}} \quad (4)$$

where

k_{10-16} =the coefficient of coupling between inductors L_{10} and L_{16}

and

$$M_{16-14} = k_{16-14} \sqrt{L_{16} L_{14}} \quad (5)$$

where

k_{16-14} =the coefficient of coupling between inductors L_{16} and L_{14}

Equation 3 may be written in the form:

$$E_{14} = \frac{-I_0 \omega^2 k_{10-16} k_{16-14} L_{16} \sqrt{L_{10} L_{14}}}{R_{16} + j\omega L_{16}} \quad (6)$$

However, since ωL_{16} , which is the inductive reactance of the coupling cylinder 16, is small in comparison with the value of R_{16} , the latter being preferably ten times as large as the former, Equation 6 simplifies into the form:

$$E_{14} = \frac{-I_0 \omega^2 k_{10-16} k_{16-14} L_{16} \sqrt{L_{10} L_{14}}}{R_{16}} \quad (7)$$

Equation 7 may also be written in the form:

$$E_{14} = -I_0 \omega k_{10-16} k_{16-14} Q_{16} \sqrt{L_{10} L_{14}} \quad (8)$$

where

Q_{16} =the ratio of inductive reactance to resistance of the coupling cylinder 16.

It will be evident from an inspection of Equation 7 that the voltage induced in the inductor 14 varies with the square of the frequency of the current flowing in the inductor 10, as previously stated. It is apparent from Equation 6 that the resistance of the coupling cylinder 16 should be made large with respect to its inductive reactance, these circuit parameters appearing in the denominator of Equation 6 and being quadrature-related impedance components.

Fig. 5 is a circuit diagram, partly schematic, of a complete electrical indicating system and represents a type of arrangement in which the adjustable coupling system of the present invention has particular utility. An indicating system of this general type is disclosed and claimed in a copending application of Harold A. Wheeler, Serial No. 470,786, filed December 31, 1942. A system of this type may be used, for example, to locate bodies of ore or metallic objects buried below the surface of the ground. This indicating system includes an amplifier 25 having input-circuit terminals 26 and output-circuit terminals 27 and having substantial amplification and a positive phase slope over a predetermined frequency range. A single feed-back path is provided for coupling the output-circuit terminals 27 to the input-circuit terminals 26, this feed-

back path including a transformer 28 and an exploring unit 29. The exploring unit 29 includes a pair of inductors 30, 31 of different diameters which are arranged in coaxial and coplanar relationship and are serially connected with opposing magnetic fields. The inductors 30 and 31 are serially included with the primary winding 32 of transformer 28 in a primary circuit which is coupled to the output-circuit terminals 27 of the amplifier 25.

The exploring unit 29 also includes a third inductor 33 having a diameter intermediate to that of the inductors 30 and 31. The inductor 33 is included in series with the secondary winding 34 of transformer 28 in a secondary circuit which is coupled to the input-circuit terminals 26 of the amplifier 25. The inductor 33 of exploring unit 29 is so positioned with relation to the inductors 30 and 31 that it normally is uncoupled to the latter and the total feed-back energy from the output-circuit terminals 27 to the input-circuit terminals 26 is thus provided primarily by the transformer 28. The component of feed-back coupling provided by the latter transformer is primarily reactive in nature; that is, the voltage induced in the secondary winding 34 of transformer 28 has a quadrature-phase relation with respect to the current flowing in the primary winding 32.

Due to metallic structural parts necessarily employed in the construction of the exploring unit 29, an undesired though small resistive component of feed-back coupling occurs in the unit 29. To compensate for this undesired feedback, the adjustable coupling system 35 of the present invention is included in the feed-back path of the amplifier 25. The first inductor 10 of the coupling system is serially connected in the primary circuit, which is coupled to the output-circuit terminals 27 of the amplifier 25, while the second inductor 14 of the coupling system is serially connected in the secondary circuit, which is coupled to the input-circuit terminals 26 of amplifier 25.

Considering briefly the operation of this indicating system, the feed-back energy provided by the transformer 28 causes the amplifier 25 to oscillate, the frequency of oscillation being such that the total phase shift through the amplifier and feed-back path is zero. If now a metallic body is brought into the vicinity of the exploring unit 29, a component of feed-back energy in quadrature relation with that provided by the transformer 28 occurs in the exploring unit 29 and has the effect of changing the phase shift of oscillations translated through the feed-back path. This results in a shift of the frequency of oscillation of amplifier 25 with the result that a beat-note signal is produced between the oscillations of amplifier 25 and a beat-note oscillator included therein. The beat-note signal is applied to an indicating device 36, thereby to indicate a change in the frequency of oscillation of the amplifier 25 thus indicating the presence of the metallic body in the vicinity of the exploring unit 29.

Since metallic structural members used in the construction of the exploring unit 29 produce the same type of coupling between the windings of exploring unit 29 as does a metallic object brought into the vicinity thereof, the system is initially balanced to compensate for the effect of such metallic structural members by suitable adjustment of the coupling system 35. This is effected by so adjusting the coupling cylinder 16 of the system 35 with relation to the inductors

10 and 14 thereof that a resistance component of coupling of the proper magnitude, and of phase opposing that introduced by the structural members of the exploring unit 29, is fed back from the output-circuit terminals 27 through the coupling system 35 to the input-circuit terminals 26 of amplifier 25. The resistance component of coupling provided by the coupling system 35 is thus just equal to but opposes that introduced by structural members of exploring unit 29 and hence the undesired effect of the latter members is compensated.

Fig. 6 represents a modified form of coupling cylinder which may be used in place of the coupling cylinder 16 of the Fig. 1 arrangement. The coupling cylinder 16' in Fig. 6 is comprised of a closed ring or cylinder having a large segment 37 of relatively large cross-sectional area and of a conductive material exhibiting relatively high electrical conductivity in order that this segment shall have a very low ratio of inductive reactance to resistance. Suitable slots 38 and 39 are provided in the ends of the segment 37 and there is secured in the slots, in conductive relation with the segment 37, a smaller segment 40 of relatively small cross-sectional area and formed of a conductive material exhibiting lower electrical conductivity or high resistance, for example nickel or Nichrome. In a particular application, the segment 37 was formed of copper bar having a one-eighth inch square cross section and bent into a three-quarter inch diameter ring, the segment 40 being formed of a sheet of nickel a few thousandths of an inch thick, one-eighth inch wide and one-eighth inch long. This form of conductive and non-magnetic inductive-coupling means has a value of resistance much greater than its value of reactance over the operating frequency range of the coupling system. In operation, a coupling system using a coupling means embodying the Fig. 6 construction operates in the same manner as that of the Fig. 1 arrangement and, hence, the description thereof will not be repeated.

In certain applications, it may be desirable to be able to provide a finite amount of coupling between the inductor 14 and one of the inductor portions 10a and 10b of the inductor 10 when the coupling cylinder 16 is positioned centrally on the inductor 14. Thus, as shown in Fig. 7, the inductor 14 may be physically positioned closer to the inductor portion 10a, for example, than to the inductor portion 10b. The coupling characteristic of an arrangement of this nature is represented by the graph of Fig. 8 from which it will be seen that a relatively large voltage of given phase is induced in the inductor 14 by current flowing in the inductor 10 when the coupling cylinder 16 is centered within the inductor 14 and that this induced voltage becomes zero only when the coupling member 16 is moved to a position where it is much closer to the inductor portion 10b than to the inductor portion 10a. It will be observed that inductor 14 has a predetermined minimum coupling with inductor 10 when cylinder 16 is in this last-mentioned position. A reversal of phase of the voltage induced in the inductor 14 is effected when the coupling cylinder 16 is moved quite close to the inductor portion 10b, but the magnitude of the induced voltage is not so large as when the coupling cylinder 16 is moved into close proximity with the inductor portion 10a.

While the operation of the invention has been explained hereinbefore on the assumption that

the inductor 10 is the primary inductor, it will be evident that a similar resistive component of coupling is provided between the inductors 10 and 14 regardless of which inductor is the primary inductor.

As illustrative of a specific embodiment of the invention, the following parameters are given for an embodiment of the invention of the type shown in Fig. 1:

Insulating member 13:

Outside diameter	inch	1/2
Slots 11, 12 and 13:		
Width	do	0.187
Depth	do	0.060
Slot separation	do	0.062

Inductor 10:

Inductor portions 10a and 10b each	9 turns of No. 26 single silk covered enameled wire wound in two layers.

Inductor 14	9 turns of No. 26 single silk covered enameled wire wound in two layers.

Coupling cylinder 16, of brass:

Outside diameter	inch	0.360
Inside diameter	do	0.308
Length	do	3/8

While it has hereinbefore been stated that the movable inductive-coupling means, comprising the cylinder 16 for example, is so disposed with reference to the inductors 10 and 14 that in a given position in its path of motion it is substantially uncoupled with at least one of the inductors and in another position in its path of motion it is substantially coupled to both of the inductors, it is to be understood that the coupling means need not in practice necessarily have a range of motion which includes these positions. For some applications, the coupling means need have only a limited range of motion, but the foregoing statement in the specification and appended claims is intended to mean that the coupling means would provide a coupling thus characterized if its range of motion were extended sufficiently to include these stated positions.

From the above description of the invention, it will be apparent that an adjustable coupling system embodying the invention has the advantages that it provides a continuous adjustment, between positive and negative limits, of the magnitude of a resistive component of coupling between two inductors. It has the additional advantage that it is aperiodic or nonselective over a wide range of operating frequencies but provides mainly a resistive coupling between its inductors of magnitude proportional to the square of the operating frequency. There is the additional advantage that the polarity of the resistive coupling may be selected as desired and the magnitude of the coupling may be continuously adjusted in an arrangement which avoids the use of any sliding contacts or flexible connectors.

While there have been described what are at present considered to be the preferred embodiments of this invention, it will be obvious to those skilled in the art that various changes and modifications may be made therein without departing from the invention, and it is, therefore, aimed in the appended claims to cover all such changes

and modifications as fall within the true spirit and scope of the invention.

What is claimed is:

1. An adjustable coupling system adapted to operate over a given frequency range comprising, a first inductor, a second inductor, a movable conductive nonmagnetic inductive-coupling means having a value of resistance greater than its value of reactance over the operating frequency range and being aperiodic and so disposed with reference to said inductors that in a given position in its path of motion it is substantially uncoupled with at least one of said inductors and in another position in its path of motion it is substantially coupled with both of said inductors, whereby said coupling means provides primarily resistance coupling between said inductors, said second inductor being so wound and disposed in the magnetic field of said first inductor that it has a predetermined minimum coupling with said first inductor for at least one position of said coupling means, and means for moving said coupling means over at least a portion of said path to adjust the value of said resistance coupling between said inductors.
2. An adjustable coupling system adapted to operate over a given frequency range comprising, a first inductor, a second inductor, a movable conductive nonmagnetic inductive-coupling means having a value of resistance greater than its value of reactance over the operating frequency range and being aperiodic and so disposed with reference to said inductors that in a given position in its path of motion it is substantially uncoupled with at least one of said inductors and in other positions in its path of motion on opposite sides of said given position it substantially couples said inductors with a polarity dependent upon the direction in said path of motion from said given position, whereby said coupling means provides primarily resistance coupling between said inductors, said second inductor being so wound and disposed in the magnetic field of said first inductor that it has a predetermined minimum coupling with said first inductor for at least one position of said coupling means, and means for moving said coupling means over at least a portion of said path to adjust the value of said resistance coupling between said inductors.
3. An adjustable coupling system adapted to operate over a given frequency range comprising, a first inductor, a second inductor, a movable conductive nonmagnetic inductive-coupling means having a value of resistance greater than its value of reactance over the operating frequency range and being aperiodic and so disposed with reference to said inductors that in a given position in its path of motion it is substantially uncoupled with one of said inductors and substantially coupled with the other of said inductors and in another position in its path of motion it is substantially coupled with both of said inductors, whereby said coupling means provides primarily resistance coupling between said inductors, said second inductor being so wound and disposed in the magnetic field of said first inductor that it has a predetermined minimum coupling with said first inductor for at least one position of said coupling means, and means for moving said coupling means over at least a portion of said path to adjust the value of said resistance coupling between said inductors.
4. An adjustable coupling system adapted to operate over a given frequency range comprising,

ing, a first inductor, a second inductor, a movable conductive nonmagnetic inductive-coupling means having a ratio of resistance to inductive reactance of the order of ten over the operating frequency range and being aperiodic and so disposed with reference to said inductors that in a given position in its path of motion it is substantially uncoupled with at least one of said inductors and in another position in its path of motion it is substantially coupled with both of said inductors, whereby said coupling means provides primarily resistance coupling between said inductors, said second inductor being so wound and disposed in the magnetic field of said first inductor that it has a predetermined minimum coupling with said first inductor for at least one position of said coupling means, and means for moving said coupling means over at least a portion of said path to adjust the value of said resistance coupling between said inductors.

5. An adjustable coupling system adapted to operate over a given frequency range comprising, a first inductor, a second inductor substantially coaxial with said first inductor, an axially movable conductive nonmagnetic inductive-coupling means having a value of resistance greater than its value of reactance over the operating frequency range and being aperiodic and so disposed with reference to said inductors that in a given position in its path of motion it is substantially uncoupled with at least one of said inductors and in another position in its path of motion it is substantially coupled with both of said inductors, whereby said coupling means provides primarily resistance coupling between said inductors, said second inductor being so wound and disposed in the magnetic field of said first inductor that it has a predetermined minimum coupling with said first inductor for at least one position of said coupling means, and means for moving said coupling means over at least a portion of said path to adjust the value of said resistance coupling between said inductors.

6. An adjustable coupling system adapted to operate over a given frequency range comprising, a first inductor, a second inductor, a movable conductive nonmagnetic inductive-coupling cylinder having a value of resistance greater than its value of reactance over the operating frequency range and being aperiodic and so disposed with reference to said inductors that in a given position in its path of motion it is substantially uncoupled with at least one of said inductors and in another position in its path of motion it is substantially coupled with both of said inductors, whereby said coupling cylinder provides primarily resistance coupling between said inductors, said second inductor being so wound and disposed in the magnetic field of said first inductor that it has a predetermined minimum coupling with said first inductor for at least one position of said coupling cylinder, and means for moving said coupling cylinder over at least a portion of said path to adjust the value of said resistance coupling between said inductors.

7. An adjustable coupling system adapted to operate over a given frequency range comprising, a first inductor, a second inductor, a thin-walled movable conductive nonmagnetic inductive-coupling cylinder having over the operating frequency range a value of resistance greater than its value of reactance, said coupling cylinder being aperiodic and so disposed with reference to said inductors that in a given position in its path of motion it is substantially uncoupled with at

least one of said inductors and in another position in its path of motion it is substantially coupled with both of said inductors, whereby said coupling cylinder provides primarily resistance coupling between said inductors, said second inductor being so wound and disposed in the magnetic field of said first inductor that it has a predetermined minimum coupling with said first inductor for at least one position of said coupling cylinder, and means for moving said coupling cylinder over at least a portion of said path to adjust the value of said resistance coupling between said inductors.

8. An adjustable coupling system adapted to operate over a given frequency range comprising, a first inductor having two spaced portions connected to have opposing magnetic fields, a second inductor positioned between the portions of said first inductor, a movable conductive nonmagnetic inductive-coupling means having a value of resistance greater than its value of reactance over the operating frequency range and being aperiodic and so disposed with reference to said inductors that in a given position in its path of motion it is substantially uncoupled with at least one of said inductors and in another position in its path of motion it is substantially coupled with both of said inductors, whereby said coupling means provides primarily resistance coupling between said inductors, said second inductor being so disposed in the magnetic field of said first inductor that it has a predetermined minimum coupling with said first inductor for at least one position of said coupling means, and means for moving said coupling means over at least a portion of said path to adjust the value of said resistance coupling between said inductors.

9. An adjustable coupling system adapted to operate over a given frequency range comprising, a first inductor having two spaced portions connected to have opposing magnetic fields, a second inductor positioned between the portions of said first inductor but closer to one portion than to the other, a movable conductive nonmagnetic inductive-coupling means having a value of resistance greater than its value of reactance over the operating frequency range and being aperiodic and so disposed with reference to said inductors that in a given position in its path of motion it is substantially uncoupled with at least one of said inductors and in other positions in its path of motion it is coupled with both of said inductors, whereby said coupling means provides primarily resistance coupling between said inductors, said second inductor being so disposed in the magnetic field of said first inductor that it has a predetermined minimum coupling with said first inductor for at least one position of said coupling means, and means for moving said coupling means over at least a portion of said path to adjust the value of said resistance coupling between said inductors.

10. An adjustable coupling system adapted to operate over a given frequency range comprising, a first inductor, a second inductor, a movable conductive nonmagnetic inductive-coupling means having over the operating frequency range a value of resistance greater than its value of reactance and comprising a closed ring having a large segment of relatively large cross-sectional area and of a material exhibiting high electrical conductivity and a smaller segment of relatively small cross-sectional area and of a material exhibiting lower electrical conductivity, said coupling means being aperiodic and so disposed with reference to said inductors that in a given position in its path

of motion it is substantially uncoupled with at least one of said inductors and in another position in its path of motion it is substantially coupled with both of said inductors, whereby said coupling means provides primarily resistance coupling between said inductors, said second inductor being so wound and disposed in the magnetic field of

5 said first inductor that it has a predetermined minimum coupling with said first inductor for at least one position of said coupling means, and means for moving said coupling means over at least a portion of said path to adjust the value of said resistance coupling between said inductors.
